UNITED STATES PATENT OFFICE.

ELMER G. SMITH, OF FOSTORIA, OHIO.

RAIL-CONNECTING MEANS.

1,141,843.

Specification of Letters Patent.

Patented June 1, 1915.

Application filed August 25, 1914. Serial No. 858,501.

To all whom it may concern:

Be it known that I, ELMER G. SMITH, a citizen of the United States, residing at Fostoria, in the county of Seneca and State of Ohio, have invented new and useful Improvements in Rail-Connecting Means, of which the following is a specification.

The present invention relates to improvements in rail connecting means, and resides 10 in the construction, combination and arrangement of parts set forth in the following specification and falling within the scope of the appended claims.

The primary object of the invention is to 15 provide a rail support in the nature of a chair member which comprises a permanent and a removable member, each of said members having an electric conductor wire associated therewith and contacting between the 20 rails and chair members to force the same into frictional contact with the rails, and to also provide simple but effective means whereby the removable member is effectively secured in its interlocking engagement with 25 the permanent member.

Other objects and advantages will appear as the nature of the invention is more fully understood, reference being had to the drawings accompanying this specification.

30 While the drawings illustrate a simple and satisfactory reduction of my improvement to practice, the nature of the invention is such that the same is susceptible of exemplification in various forms and changes in proportion 35 and degree, so I am not to be restricted to the showing therein, but am entitled to all such changes as fall within the scope of the appended claims.

In the drawings: Figure 1 is a perspective view illustrating two rails connected in accordance with my invention, Fig. 2 is a top plan view of the same, Fig. 3 is a transverse section on the line 3—3 of Fig. 2, Fig. 4 is a similar view on the line 4—4 of Fig. 2, Fig. 45 5 is a perspective view of one of the joint chair members, and Fig. 6 is a similar view of the second and removable chair member. Fig. 7 is a horizontal sectional view taken in a line with the conductor wires and illustrating the manner in which the said wires 50 are received within the channels in the webs of the rails, Fig. 8 is a detail horizontal sectional view illustrating the manner in which the spring pressed pin 18 engages with one of the depressions or sockets 28 in the member 19.

55 My improved rail fastener may be of a size to fit upon two ties and have the roadbed tamped thereunder, and the same may have its ends also secured to the adjacent ties, but the device also may rest upon any number of ties and be secured thereto in any desired or preferred manner.

60 The improvement contemplates a chair which is broadly designated by the character C and which is adapted to receive and support the ends of two rails R—R which are of the ordinary construction and which rest upon ties T.

65 The chair comprises a base 1 which, in the showing of the drawings, is of a length corresponding to the distance between two of the ties T, and the said base may be secured to the tie if desired. The roadbed is tamped beneath the ties to bring the base flush with the upper faces of the ties. The base 3 has integrally formed upon one of its longitudinal edges a vertically projecting portion 4 having an inwardly extending angular flange 5 which is shaped to correspond with the shape of one side of the rail engaging both the base and within the fishing spaces of the said rails. The lower angular face 70 of the flange 5 is provided with a lug 6 that is also formed with the lower or horizontal face in the rail receiving portion of the chair, and the base flanges of the rails, to one of their sides and at their meeting ends are notched, as at 7, to engage with the lug 6. This lug 6 prevents either of the rails 75 creeping toward the other rail and also limits the movement of the rails toward each other when the same are contracted by cold. Secured within suitable openings in the vertical member of the rail engaging flange 5 80 are the ends of a conductor wire 8, which extends longitudinally a suitable distance in both directions from the center of the flange 5, and the webs of the rails at their meeting ends may be, and preferably are, provided 85 with registering depressions or channels 9 to receive the wire. This wire not only serves as a positive conducting member between the rails but also sufficiently contacts 90 with the rails to force the same away from the flange 5, and by reference to the drawings it will be noted that the holes or openings which receive the ends of the wire are 95 100 105

flared or inclined toward the opposite sides of the chair.

The base receiving portion of the chair is provided, at a distance beyond the inner face 5 of the flange or side 5, with a channel 10 which is horizontally straight and which has its shoulder 11 parallel with, but, as stated, a distance beyond the inner vertically straight rail engaging portions of the flange 10 or side 5. The opposite vertical wall 13 inclines from one of the ends of the chair to the opposite end thereof, a horizontally straight flange projecting inwardly beyond the said angular wall 13, and this flange has its lower face arranged in a line with or flush with the horizontal rail receiving wall 12. The overlying portion or ledge 14 has its inner face arranged parallel with the angular wall or shoulder 13, and the chair 20 is cut away above the ledge 14 to provide a longitudinally extending tongue, which is designated by the numeral 16. The vertically disposed wall above the tongue 16 is arranged at an angle or is parallel with the 25 face 14 of the tongue 16, and the said angular wall 17 is also beveled inwardly from its upper corner. The member providing the angular wall 17, adjacent the reduced end thereof, is formed with a transverse socket 30 for the reception of a spring pressed pin 18, the purpose of which will presently be described.

The numeral 19 designates the removable member for the chair. This member includes a base 20 which is horizontally flat and of a thickness equaling the distance between the walls or floors 10 and 12 and the distance between the tongue 16 and the wall 11. The inner edge of the base 20, which is 35 designated by the numeral 21, is longitudinally straight, or is arranged at a right angle to its straight ends, but the opposite side 22 of said base is arranged at an inclination, that is, the said wall is of a lesser 40 width at one end of the chair than at the other end. The base is provided upon its inner face and at a distance from its inner wall 21 with an angularly disposed side or flange 23 which is of a similar formation to 45 that of the flange 5, the same being adapted to overlie the base flanges of the rails and to engage within the fishing spaces thereof, and the vertical inner face of the said flange is provided with a longitudinally extending 50 conductor wire 24 which has its ends received in laterally disposed openings, and if desired, a portion of said wire may be received within a longitudinally extending groove provided in the face 24.

55 The outer inclined wall 22 is formed with a longitudinally extending channel 25 providing the upper edge of said wall with a beveled as well as an inclined face 26 and the inner wall provided by the said groove 60 25 is arranged parallel with the walls 22 and

26, so that the tongue 16 may be received within the said groove. The wall 22 contacts with the wall 13 and the removable member is arranged upon the stationary member and the wall 26 being shaped to 70 agree with the wall 17 is engaged and partially overlapped by the said wall 17. The wall 26 at its enlarged end is provided with a plurality of depressions or sockets 28, any of which being adapted to be engaged by 75 the rounded head of the spring pressed pin 18. It is to be here stated that the depressions 28 are in alinement, and the guiding walls between the same are concaved so that the member 19 may be driven the desired 80 distance upon the stationary member of the chair without injury to the pin.

The numeral 50 designates a headed bolt member having its shank provided with a bore within which the pin 18 is received, the 85 spring being arranged between the pin and the inner wall of the bore, and the bolt member 50 is, of course, removable to permit of the pin being disengaged from the depressions or sockets 28 in the member 19 to permit of the removal of said member 19.

From the above description, taken in connection with the accompanying drawings, the simplicity of the device as well as the advantages thereof will, it is thought, be 95 perfectly apparent to those skilled in the art to which such invention appertains without further detailed description.

Having thus described the invention, what I claim is:

1. In a rail joint, a chair including a base upon which the rails rest and having a flange for engaging the rails, the said base having a longitudinally channeled portion, one of the longitudinal walls of which being inclined from one end of the base to the opposite end thereof, the said inclined wall being grooved parallel with the horizontal portion of the channel, to provide a tongue, a removable member having one of its sides formed with a flange to engage the rails, and its opposite side inclined from one of its ends to its opposite end, the said inclined side being channeled to receive the tongue of the chair, and automatic means for locking the removable member upon the chair member.

2. A rail joint including a chair having a base upon which the rails rest, the base having one of its sides formed with a rail engaging flange, the said base being channeled longitudinally and the outer wall of the said channeled portion being grooved to provide a tongue, a removable member having a base, a portion of which underlies the base of the rails, and being formed with a flange which engages with the sides of the rails, the opposite side of the removable member being provided with a groove to receive the tongue of the chair, a spring pressed pin upon the 130

chair, and the removable member having depressions arranged in a line with the spring pressed member to receive the said member to lock the movable member upon 5 the chair proper.

3. A rail chair including a base upon which the rails rest, and which has one of its sides formed with a flange to engage with the sides of the rails, the said base having 10 a longitudinal channel within the rail seat, the outer wall of the channel being inclined from one of the ends of the chair to the opposite end thereof, the said outer wall having a lower groove and an upper groove providing 15 a tongue, the walls of the groove and tongue agreeing with the inclination of the said side, the upper wall being beveled, the said upper wall at the reduced end of the chair having a spring pressed pin, a removable 20 member including a base which has its inner side provided with a flange which engages with the rail, and the said base below the flange receiving the portions of the

rail projecting beyond the rail seat of the chair proper, the opposite side of the removable member being inclined from one of its ends to the opposite end thereof to agree with the inclined walls of the chair proper, 25 said outer wall of the removable member being centrally grooved to receive the tongue 30 of the chair, the wall above the groove being beveled and co-acting with the beveled upper wall of the chair proper, and the said beveled wall of the removable member being provided with a plurality of intersecting depressions any one of which receiving the spring pressed member of the chair proper 35 to retain the removable member upon the chair.

In testimony whereof I affix my signature 40 in presence of two witnesses.

ELMER G. SMITH.
